UNITED STATES PATENT OFFICE

ROBERT FARIES, OF ST. DAVIDS, PENNSYLVANIA

RAIL JOINT

Application filed July 25, 1932. Serial No. 624,479.

This invention relates to track rail joints of the customary type wherein the contiguous ends of adjoining rails are overlapped by joint bars which fit the side hollows of the rails, and which are secured by bolts passing through registering apertures in the joint bars and the webs of the rails. More particularly, the present invention relates to a rail joint wherein spring shims are disposed 5 within the fishing spaces between the joint bars and rails at particular areas of the joint, the shims having wedge-shaped tongues which are constantly and independently urged outward across such fishing spaces to 10 compensate for wear.

The principal object of the invention is to render a rail joint self-tightening with capacity to compensate for wear between the undersides of the heads of the rails and the 15 subjacent surfaces of the joint bars, and between the base flanges of the rails and the base surfaces of the joint bars at the regions where wear is most likely to occur. This object I attain, as hereinafter fully set forth, 20 through the provision of spring shims which are distorted from natural shape incident to the drawing together of the joint bars when the joint is assembled, the shims having tongues which are constantly urged outward 25 across the fishing spaces at the regions where they are applied by virtue of their inherent resiliency and their distortion from natural shape.

A further object of my invention is to provide in a rail joint a set of spring shims located in pairs with respect to the length of the joint, one such pair being disposed at the ends of the bar with its outwardly projecting tongues engaging in the fishing spaces 30 between the rail flanges and the lower surfaces of the joint bar; and the other such pair being disposed at the center of the joint, with one shim at each side of the gap between the rail ends, and with their wedge-shaped tongues projecting outwardly in the fishing spaces between the rail heads at their ends and the top surface of the center of the joint bar.

The present invention differs from that 35 shown in my pending application for U. S.

Letters Patent, Serial No. 592,264, filed February 11, 1932, in that the spring shims which are here utilized are disposed interiorly of the joint bar, with their tongues urged outwardly across the fishing spaces, whereas in 55 the application referred to, the spring shims are shown disposed exteriorly of the joint bars with their wedge-shaped tongues urged inwardly across the fishing spaces between the bars and rails.

Other objects and advantages characteristic of my invention will become more apparent from the detailed description which follows hereinafter, having reference to the accompanying drawings, wherein there is illustrated an example or embodiment of my invention, and certain modifications or alternative forms which the invention may take. Of the drawings:

Fig. I represents, in perspective, a rail joint embodying the present invention, with a portion of a joint bar broken away to reveal the interior of the joint.

Fig. II represents an enlarged side elevation of the rail joint of Fig. I.

Fig. III represents a cross section of the same, taken as indicated by the lines III—III of Fig. II.

Fig. IV represents a perspective view of one of the spring shims of the rail joint of 30 the preceding figures.

Fig. V represents a view similar to that of Fig. III showing a rail joint of my invention wherein the joint bars are modified as to cross sectional shape.

Fig. VI represents a side elevation of another type of rail joint of my invention wherein the spring shims and joint bars are further modified, with a portion of a joint bar broken away to reveal the interior of the joint.

Fig. VII represents a cross section of the same, taken as indicated by the lines VII—VII of Fig. VI.

Fig. VIII represents a view similar to that of Fig. VII, showing the position occupied by the spring shim before the joint bar is drawn up.

Fig. IX represents a cross section of the 100

same, taken as indicated by the lines IX-IX of Fig. VI; and,

Fig X represents a view similar to that of Fig. IX showing the position occupied by the spring shim before the joint bar is drawn up.

With reference to Figs. I to IV of the drawings, the numerals 1 and 2 designate adjoining rails, the numeral 3 designates the joint bars which fit the hollows at opposite sides of the rails; and the numerals 4 and 5, the center and end fastening means, in the form of clamp bolts, whereby the several parts are secured together, the bolts engaging through registering apertures respectively in said rails and the joint bars, all in the manner well understood in the art.

In the example of my invention shown in Figs. I to III, the joint bars 3 are made of less fishing height than the fishing height of the rails. Each joint bar comprises a head portion 6, a web portion 7 and a foot portion 8. In the fishing spaces between the rails 1, 2 and the joint bars 3, spring shims 9, 10 are interposed, there being four such shims at each side of the rail joint in the illustrated example of my invention.

Each spring shim 9, 10 is made of resilient metal and naturally assumes a shape such as shown in Fig. IV, in which the web portion 11 is smoothly rounded and the upper and lower tongues 12, 13 form an obtuse angle with the web portion. The tongues 12, 13 are tapered, presenting a wedge shaped cross section.

When the shims 9, 10 are assembled in a rail joint, their wedge shaped tongues 12, 13 project laterally outward in the fishing spaces between the surfaces 14 at the undersides of the rail heads and the surfaces 15 of the joint bar head 6, as well as between the sloping surfaces 16 of the rail flanges and the sloping surfaces 17 of the foot portions 8 of the joint bars. Incident to the drawing together of the joint bars 3, in the assembly of the rail joint, the web portions 11 of the spring shims 9, 10 are caused to be flattened against the web 18 of the rail. To illustrate this distortion from natural shape, there is shown in Fig. III, in broken lines at 19, the curvature which is normally assumed by the web portions 11 of the spring shims 9, 10. When the joint bars 3 are drawn together by tightening the nuts 20 on the bolts 4, 5, the resulting flattening of the spring shims 9, 10 causes their wedge shaped tongues 12, 13 to be drawn inward and to assume a less obtuse angle with the web portion 11 than is normally the case. Accordingly, the tongues 12, 13 are placed under stress, incident to the drawing together of the joint bars 3, and they are constantly urged outwardly across the fishing spaces so that as wear occurs in the rail and joint bar surfaces at these spaces,

the tongues spring outwardly and take up or compensate for the wear.

The center shims 9, 10 are disposed at each side of the gap between the rails 1, 2 and are each split at their upper ends to form two separate sections 21, 22, one of greater width than the other. The section 21 is disposed adjacent to the end of the rail 1. Similarly the end shims 9, 10 are split at their base portions to form separate sections 23, 24. Thus along the length of the rail joint there are a series of tongue sections 21, 22, 23, 24, independently urged outward across the fishing spaces, and if the wear is more pronounced at certain regions rather than at others, the tongue sections at the particular regions where pronounced wear occurs have capacity to flex independently of the other tongue sections and thus to compensate for uneven wear. Ordinarily the wear is most pronounced at the center of a rail joint beneath the rail heads and at the ends of the joint above the rail flanges. For this reason I prefer to employ the relatively short tongue sections 21, 23 at these areas. Obviously, however, the shims contemplated by this invention may take a variety of different forms. In the form illustrated the center shim 9 on the rail 1 is identical and interchangeable with the end shim 9 on the rail 1, and likewise the center shim 10 on the rail 2 is identical and interchangeable with the end shim 10 on the rail.

In Fig. V there is shown a modification of my invention in which a different type of joint bar is employed. The joint bar 3a there shown is provided with longitudinal inwardly projecting ribs 25, 26. The ribs 25, 26 bear upon the web portions 11 of the spring shims 9, 10, and cause the spring shims to be flattened against the web 18 of the rail incident to the drawing together of the joint bars. In the regions above and below the ribs 25, 26, the joint bars 3a are cut away as indicated at 27 and 28, respectively, so as not to interfere with the flexure of the tongues 12, 13 at these regions, it being important that there be no obstruction to the change in shape of the shims as wear occurs so that their tongues may move outward freely to compensate for such wear.

In Figs. VI to X, inclusive, there is shown a further modification of my invention in which separate head and base shims are employed. The head shims are designated at 29 and 30, whereas the base shims are designated at 31 and 32. As indicated in Fig. VI, the joint bars 3b employed in this example of my invention are of somewhat different form than the joint bars 3 shown in Figs. I, II and III. The joint bars 3b are each offset vertically in such manner as to provide a recess 33 in the medial portion of the joint beneath the underside of the heads of the rails 1, 2, and additional recessed areas 34 at the ends of the

joint above the base flanges of the rails.

In Figs. VII and VIII, the base shims 31 and 32 are clearly shown. In Fig. VIII these shims are shown in the position which they occupy just prior to the drawing together of the joint bars 3b by tightening of the nuts 20 on the bolts 5. In this position the base shims 31, 32 have their flat inner end portions 35 bearing against the webs of the joint bars 3b, and there is a smoothly rounded curve in the body portion 36 of the shims between their inner end portions 35 and their wedge shaped tongues 37. The tongues 37 project outwardly in the fishing spaces at the recessed areas 34 of the joint bars 3b. When the nuts 20 are tightened on the bolts 5 drawing together the joint bars 3b, the base shims 31, 32 are distorted from their natural shape and assume the shape shown in Fig. VII. In this position, the inner end portions 35 bear firmly against the webs of the joint bars 3b and are held against upward movement by the bolts 5. The body portion 36 of each shim 31, 32, instead of being smoothly curved as shown in Fig. VIII, is crimped or distorted from natural shape in such manner as to tend to urge the tongues 37 outward in the recessed areas 34. The base shims 31, 32 are preferably split as shown in Fig. VI to provide two tongue sections 38, 39, each section having capacity for independent flexure.

In Figs. IX and X, the head shims 29, 30 employed in this rail joint are clearly shown. As seen in Fig. X, prior to the drawing together of the joint bars 3b by tightening of the nuts 20 on the center bolts 4, the inner end portions 40 of the head shims 29, 30 bear against the web portions of the joint bars 3b, the body portions 41 of the head shims 29, 30 assume a smoothly rounded shape, and the tongues 42 project laterally outward in the fishing spaces at the recessed areas 33 of the joint bars 3b. When the rail joint is completely assembled, as shown in Fig. IX, the body portions 41 of the head shims 29, 30, instead of being smoothly rounded as shown in Fig. X, are crimped or distorted from natural shape in such manner as to tend to urge the tongues 42 outward across the fishing spaces beneath the undersides of the rail heads. The head shims 29, 30 are preferably split to form separate tongue sections 43, 44 which have capacity for independent flexure in the fishing spaces across which they project.

It will be especially noted that in all of the above examples of my invention, independently flexible spring shims are utilized at intervals along the length of a rail joint and are disposed at the primary bearing regions where wear is most likely to occur. It will also be apparent that, as wear takes place at these regions, the wedge-shaped tongues of the shims are urged outwardly across the fishing spaces to take up or compensate for

such wear. Accordingly, the rail joint of this invention is rendered self-tightening and can continue in service after the joint bars have become unevenly worn, still effectively trussing the rail joint and preventing the condition known as "low joints" from occurring.

While I have described several embodiments or examples of my invention, having reference to specific forms which the joint bars and shims may take, it will be apparent that numerous changes may be made in the particular form of these elements, and that certain features of my invention may at times be used to advantage without a corresponding use of other features, all without departing from the spirit of the invention as defined in the claims hereto annexed.

Having thus described my invention, I claim:

1. In a rail joint, the rails and joint bars, and a spring shim therebetween having a wedge-shaped tongue interposed in the fishing space between a bar and a rail, said shim being distorted from natural shape incident to the drawing together of the bars when the joint is assembled, whereby said tongue is constantly urged outwardly across said fishing space.

2. In a rail joint, the rails and joint bars, and a spring shim having a portion bearing against the web of the rail and a wedge-shaped tongue extending across the fishing space between a bar and a rail, said rail engaging portion of the shim being changed in shape incident to the drawing together of the bars, whereby said tongue is urged outwardly across said fishing space.

3. In a rail joint, the rails and joint bars, and a spring shim having a curved portion bearing against the web of the rail and a wedge-shaped tongue extending across the fishing space between a bar and a rail, said curved portion being distorted from its natural shape incident to the drawing together of the bars, whereby said tongue is urged outwardly across said fishing space.

4. In a rail joint, the rails and joint bars, and a spring shim having a smoothly curved web portion and a wedge-shaped tongue interposed in the fishing space between a bar and a rail, the web portion of said shim being flattened against the web of the rail incident to the drawing together of the bars when the joint is assembled, whereby said tongue is constantly urged outward across said fishing space.

5. In a rail joint, the rails and joint bars, and a spring shim having a smoothly curved web portion and wedge-shaped upper and lower tongues interposed in the fishing spaces between a bar and rail, the web portion of said shim being flattened against the web of the rail incident to the drawing together of

the bars when the joint is assembled, whereby said tongues are constantly urged outward across said fishing spaces.

6. In a rail joint, the rails and joint bars, and a spring shim having a split tongue in the fishing space between a bar and a rail, said shim being distorted from natural shape incident to the drawing together of the bars when the joint is assembled, and the sections of said split tongue being urged outward across said fishing space.

7. In a rail joint, the rails and joint bars, and spring shims fitting the hollow of the rails, one at each end of the joint bar and one at each rail end, said shims having tongues interposed in the fishing spaces between the bar and rails and being distorted from natural shape incident to the drawing together of the bars when the joint is assembled whereby said tongues are constantly urged outward across said fishing spaces.

8. In a rail joint, the rails and joint bars, and spring shims fitting the hollow of the rails one at each end of the joint bar and one at each rail end, said shims having split tongues in the fishing spaces beneath the rail heads at the ends thereof and above the rail flanges at the ends of the joint bar, and said shims being distorted from natural shape incident to the drawing together of the bars when the joint is assembled whereby the sections of said split tongues are urged outward across said fishing spaces.

9. In a rail joint, the rails and joint bars, and spring shims fitting the hollow of the rails, said shims having wedge-shaped tongues interposed in the fishing spaces beneath the rail heads at the ends thereof and above the rail flanges at the ends of the joint bar, and said shims having smoothly curved web portions flattened against the rail webs incident to the drawing together of the bars when the joint is assembled, whereby said tongues are constantly urged across said fishing spaces.

45

50

60

65

10. In a rail joint, the rails and joint bars, bolts for fastening the joint bars to the rails, and a spring shim disposed between a rail and joint bar, one end of said shim bearing against a bolt and the other end of said shim being formed with a tongue extending laterally across the fishing space between said bar and rail, said shim being distorted from natural shape incident to its assembly in the rail joint, whereby said tongue is urged outwardly across said fishing space.

11. In a rail joint, the rails and joint bars, bolts for fastening the joint bars to the rails, and spring shims disposed between the rails and joint bars at intervals of the length of the joint, said shims being arranged with their inner ends bearing against the bolts and their outer ends formed with tongues extending laterally across the fishing spaces between said bars and rails at the center of the joint beneath the rail heads and at the ends of the joint above the rail flanges, said shims being distorted from natural shape incident to their assembly in the rail joint, whereby said tongues are urged outwardly across said fishing spaces.

12. In a rail joint, the rails, joint bars joining the rail ends, said bars having recessed areas in their head and foot portions, and spring shims disposed between said rails and joint bars, said shims having tongues extending laterally across the recessed areas of said bars, and said shims being distorted from natural shape incident to the drawing together of the bars when the joint is assembled, whereby said tongues are urged outwardly across said recessed areas of the joint bars.

In testimony whereof, I have hereunto signed my name at Philadelphia, Pennsylvania, this 21st day of July, 1932.

ROBERT FARIES.
